PLAYGROUND SWING

Calvin R. Kurrasch, 2315 N. Olive Lane,
Santa Ana, Calif.

Filed Mar. 26, 1965, Ser. No. 84,449

Term of patent 14 years

(Cl. D34—5)

FIG. 1.

FIG. 2.

FIG. 3.

FIG. 4.

FIG. 5.

I claim:

The ornamental design for a playground swing, substantially as shown.
